US0D1043085S

(12) **United States Design Patent** (10) Patent No.: **US D1,043,085 S**
(45) Date of Patent: ** Sep. 24, 2024

(54) **SHOE UPPER**

(71) Applicant: **Skechers U.S.A., Inc. II**, Manhattan Beach, CA (US)

(72) Inventors: **Jennifer Fosburg**, Manhattan Beach, CA (US); **Bin Wang**, Manhattan Beach, CA (US); **Hui Xie**, Dongguan (CN)

(73) Assignee: **Skechers U.S.A., Inc. II**, Manhattan Beach, CA (US)

(**) Term: **15 Years**

(21) Appl. No.: **29/933,499**

(22) Filed: **Mar. 20, 2024**

FOREIGN PATENT DOCUMENTS

DE 10247163 11/2015

Primary Examiner — Jonathan J Han

(74) *Attorney, Agent, or Firm* — Marshall A. Lerner; Steven J. Kim; Kleinberg & Lerner, LLP

(57) **CLAIM**

The ornamental design for a shoe upper, as shown and described.

DESCRIPTION

FIG. 1 is a front perspective view of a shoe upper in accordance with my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

Broken lines shown in the drawing represent environmental structure of the shoe and form no part of the claimed design.
